Filed Mar. 24, 1975, Ser. No. 561,670

Term of patent 14 years

Int. Cl. D19—06

U.S. Cl. D19—78

FIG. 1 is a front perspective view of a combined note paper dispenser and pen holder with pen showing my new design;

FIG. 2 is an exploded perspective view thereof;

FIG. 3 is a rear perspective view of the holder portion, the pen being omitted for convenience of illustration;

FIG. 4 is a top plan view thereof;

FIG. 5 is a bottom plan view thereof.

The side of the pen opposite that shown in FIGS. 1 and 2 is a mirror image of the side shown in FIGS. 1 and 2.

I claim:

The ornamental design for a combined note paper dispenser and pen holder with pen, substantially as shown and described.
